[57] CLAIM

The ornamental design for telephone base support, as shown and described.

DESCRIPTION

FIG. 1 is a rear, bottom, and left side perspective view of a telephone base support showing my new design;
FIG. 2 is a left side elevational view thereof, the right side being a mirror image;

FIG. 3 is a bottom plan view in place on a telephone base; and,

FIG. 4 is a bottom plan view partially slid into position on a telephone base.

The surfaces not shown have the same flat continuous appearance as those shown.

The broken lines showings of a telephone base in FIGS. 3 and 4 are for illustrative purposes only and form no part of the claimed design.
